T. J. ELLISON

MOP HOLDER

Filed July 21, 1923

Inventor
Thomas J. Ellison

Milo B. Stevens Co.

Homage

UNITED STATES PATENT OFFICE.

THOMAS J. ELLISON, OF RICHMOND, KENTUCKY.

MOP HOLDER.

Application filed July 21, 1923. Serial No. 652,927.

To all whom it may concern:

Be it known that I, THOMAS J. ELLISON, a citizen of the United States, residing at Richmond, in the county of Madison and 5 State of Kentucky, have invented new and useful Improvements in Mop Holders, of which the following is a specification.

My invention relates to mop holders and has for one of its primary objects the provision 10 of a device of this character wherein a yieldable clamping expedient is employed for holding the mop in said device.

As a further object the invention contemplates a means whereby the mop-engaging portion may be adjusted to grip mops of 15 varying thicknesses, an improved yieldable clamping means being associated with said mop-engaging member for maintaining the same in a predetermined position.

20 A still further object of the invention is to furnish a mop holder of this character wherein the mop-engaging portion is formed entirely of wire, thus making the holder more or less flexible to facilitate mopping in 25 corners and along walls without liability of scarring the same as would be the case were the holder of a rigid construction.

And I might state further that it is my 30 object to create a mop holder which although of a very simple and inexpensive structure, will be strong and durable and highly efficient in practical use.

The above and other objects to be developed during the course of the detailed 35 description appearing hereinafter, are attained by means of a novel combination and arrangement of parts to be hereinafter described and claimed, and in order that the same may be better understood, reference is 40 had to the accompanying drawing forming a part of this specification and wherein the preferred embodiment of the invention is disclosed.

In the drawing,

45 Figure 1 is a plan view, partly broken, illustrating a mop holder constructed in accordance with my invention;

Fig. 2 is a sectional view taken on the line 2—2 of Fig. 1, and

50 Fig. 3 is a section on the line 3—3 of Fig. 1 looking in the direction of the arrows.

Referring specifically to the drawing, wherein like reference characters have been

used throughout to designate similar parts, 55 numeral 5 denotes a mop handle of the usual wooden type, the end of which is apertured to receive the inturned ends 6^a of the cross piece or head of the holder 6. The holder 6 is formed of one piece of relatively heavy wire which is doubled as clearly shown in 60 Figs. 1 and 2, the outer ends of which are twisted to form eyes 7 which function as guides for a yoke 8 which is also formed of relatively stiff wire.

The front portion of the yoke 8, denoted 65 at 8^a, is parallel to the cross piece 6 and is adaptable for clamping a mop 9 against the cross piece 6 upon retraction of the yoke 8 through the eyes 7.

The rear portion of the yoke 8 is bent 70 laterally as indicated at 10, the free end of which is formed with a hook which is engageable in an eye at the upper end of the opposite yoke side as indicated at 11. Intermediate the ends of the portion 10 two 75 loops 10^a are formed in normally spaced relation by twice curling the wire backwards on itself in each instance, the double formation of these loops being best shown in Fig. 3. The purpose of this construction just 80 referred to will presently become apparent.

The means for holding the yoke 8 so that its portion 8^a will grip the mop 9 will now be referred to, the same comprising a piece of heavy wire 12, the free ends of which are bent for insertion transversely through apertures in the handle 5 as shown in Fig. 2, the terminal portions of said ends being bent along the other side of the handle as indicated at 12^a whereby the rigid attachment of the member will be assured. The stock of the wire between the handle carried portions thereof is bent to form a plurality of humps 13, over a selected one of which the lateral portion 10 of the yoke intermediate the loops 10^a is hooked for clamping the portion 8^a of the yoke against the mop 9 in 90 an obvious manner.

The looped portions 10^a function to stiffen 100 the medial portion of the part 10 and form 100 springs which permit flexation of the outer portions of the member 10 to yieldably clamp the mop 9 in position. It will also be apparent from the drawing that upon 105 clamping of the mop 9 between the portions 8^a and 6, that the loops 10^a will be moved

slightly towards each other to engage the sides of the selected hump 13 over which the medial portion of the wire 10 is hooked thus preventing dislodgment of the yoke from 5 clamping position with the subsequent free 10 ing of the mop 9.

Should a handle 5 be provided with a split clamping end for holding the inturned 15 ends 6^a of the cross piece 6, a collar or band 10 14 will be provided for clamping the inturned portions 6^a in the end of the handle.

In accordance with the patent statutes, I 15 have described and illustrated herein the preferred embodiment of my invention, but 20 since various changes and modifications thereof will immediately suggest themselves to those skilled in the art without departing from the spirit of my invention, it will be distinctly understood that I reserve the 25 right to make such changes as fairly fall within the spirit and scope of the appended 30 claims.

It will also be apparent from an inspection 25 of the drawing, particularly Fig. 1, that the loops 10^a have an additional function to those referred to hereinbefore, in that they act as finger receiving loops during the manual adjustment of the yoke for either engaging or disengaging the cleaning 30 element.

Having thus described my invention, what I claim as new and desire to secure by Letters Patent is:

1. A mop holder comprising a handle having a head provided with guides, a yoke 35 slideable through said guides and having a cross member formed with spring loops, and a rack having sockets to selectively receive a portion of said cross member of the yoke to hold the yoke in a set position, said spring 40 loops being arranged on opposite sides of and constantly exerting spring pressure on said rack to hold the cross member in one of said sockets and said spring loops defining finger receiving members. 45

2. A mop holder comprising a handle having a head, a substantially rectangular yoke 50 slidably associated with said head and adapted to co-operate with the head in gripping a mop, and a rack carried by said handle and having a plurality of holding members selectively engaged by a portion of 55 said yoke, said yoke being provided with spring loops arranged on opposite sides of and adapted to be moved into pressure contact with said rack by the pressure of the mop on the yoke.

In testimony whereof I affix my signature.

THOMAS J. ELLISON.
